(57) **CLAIM**

The ornamental design for a shaped protective cover for a door fixture, as shown and described.

DESCRIPTION

FIG. 1 is a top view of a shaped protective cover for a door fixture of the present design;

FIG. 2 is a bottom view of the shaped protective cover for a door fixture of the present design;

FIG. 3 is a rear view of the shaped protective cover for a door fixture of the present design;

FIG. 4 is a front view of the shaped protective cover for a door fixture of the present design;

FIG. 5 is a left side view of the shaped protective cover for a door fixture of the present design;

FIG. 6 is a right side view of the shaped protective cover for a door fixture of the present design;

FIG. 7 is a top rear perspective view of a first embodiment of a shaped protective cover for a door fixture of the present design; and,

FIG. 8 is a top rear perspective view of a second embodiment of a shaped protective cover for a door fixture of the present design.

The break lines in the drawings depict the boundaries of the Claim. The article between the break lines forms no part of the claimed design.
